ILLUMINABLE CHRISTMAS PLAQUE

Abraham Abramson, New York, N. Y., assignor to Raylite Electric Corp., Bronx, N. Y., a corporation of New York

Application April 16, 1956, Serial No. 41,089

Term of patent 14 years

(Cl. D29—23)

Fig. 1.

Fig. 2.

Fig. 1 is a front elevational view of an illuminable Christmas plaque showing my new design, and

Fig. 2 is a top plan view thereof.

I claim:

The ornamental design for an illuminable Christmas plaque, as shown.
